Atty's.

UNITED STATES PATENT OFFICE.

GUSTAF A. CARLSON, OF CHICAGO, ILLINOIS, ASSIGNOR TO THE BOYE NEEDLE COMPANY, OF CHICAGO, ILLINOIS, A CORPORATION OF ILLINOIS.

CURTAIN-ROD.

1,315,706.

Specification of Letters Patent. Patented Sept. 9, 1919.

Application filed October 28, 1918. Serial No. 259,967.

To all whom it may concern:

Be it known that I, GUSTAF A. CARLSON, a citizen of Sweden, who have taken out first papers for citizenship in the United States, 5 residing at Chicago, in the county of Cook and State of Illinois, have invented a new and useful Improvement in Curtain-Rods, of which the following is a specification.

This invention relates particularly to 10 flexible curtain-rods, such as are commonly employed for sash-curtains, and more especially to curtain-rods which comprise a close-wound spring wire coil, or coils.

The primary object is to provide a simple 15 and effective connection between the coil or coils comprising the curtain-rod and the brackets which are adapted for connection with a window-frame, or sash.

The invention is illustrated in the accompanying drawing, in which—

Figure 1 represents a broken plan view, showing the curtain-rod applied to a sash or window-frame by means of the improved bracket connections; Fig. 2, a broken elevational view of the same; Fig. 3, a broken elevational view showing the device in somewhat modified form; Fig. 4, a broken sectional view taken as indicated at line 4 of Fig. 2; Fig. 5, a broken sectional view showing the form of connection used in Fig. 3; and Fig. 6, a broken sectional view illustrating a further modification of the device.

Referring to Figs. 1, 2 and 4, A represents 35 a window-frame, or sash; B, a flexible curtain-rod comprising a close-wound, resilient coiled wire section or sections; and C, the improved bracket connection between the flexible curtain-rod and the sash or frame. 40 The rod B may comprise a length of close-wound piano steel wire, as indicated in the drawing; or it may comprise a pair of sections of coiled wire and an intermediate rod-section connected with the coiled wire 45 sections, as illustrated, for instance, in my co-pending application No. 259,965, filed of even date herewith.

Each of the brackets C comprises a base-portion 1 adapted to be connected with the 50 sash by means of screws, and an arm 1^a equipped with a longitudinally curved sleeve, or channel, 1^b. The end-portion of the coiled wire member B extends freely, but snugly, through the curved sleeve 1^b and is 55 secured therein by means of a pin, or short

rod, 2, which is equipped with a knob, or handle, 2^a. The member 2 is a straight member. In making the connection, the end-portion of the coiled wire member B is slipped through the curved sleeve 1^b until 60 the end projects somewhat, the pin 2 is then inserted, and the member B is then allowed to contract until the end-portion is drawn into the sleeve, as appears from Fig. 4. The introduction of the member 2 creates a binding action, inasmuch as the coiled wire member cannot freely follow the curve of the sleeve 1^b. In forming the connection, the member B is stretched sufficiently to give it 65 the desired tension and the connection is 70 formed in the manner shown in Fig. 4. When it is desired to disconnect the member B from the bracket C, this may be accomplished by stretching the member B and forcing the end-portion through the sleeve, 75 and then withdrawing the pin or plug, after which the end-portion of the coil will slip freely through the curved sleeve.

In the construction shown in Figs. 3 and 5, C¹ represents the bracket. In this case, 80 the curvature of the sleeve 1^b is in a plane parallel with the sash, or frame, A. The pin or plug is designated 2^b. Its action is the same as in the first-described construction.

In the modification shown in Fig. 6, C² represents the bracket, which in this case is 85 equipped with a straight sleeve 1^b. The coil B is inserted through the sleeve, and a pin, or plug, 2^c is inserted into the end of the 90 coil, the pin being provided with an off-set or deformation 3. When the end-portion of the coil is withdrawn into the sleeve, a binding action results by reason of the off-set 3, so that the wire coil will be securely held in 95 the tube.

In each of the illustrations given, the pin or plug employed is adapted to produce a deformation of the wire coil with relation to the channel of the bracket, so that a binding 100 action is attained which effects a secure connection between the flexible curtain-rod and the bracket.

The improved device is inexpensive, neat in appearance, thoroughly adapted to its 105 purpose, and capable of being manipulated with facility.

The foregoing detailed description has been given for clearness of understanding only, and no unnecessary limitations should 110

be understood therefrom, but the appended claims should be construed as broadly as permissible, in view of the prior art.

What I regard as new, and desire to secure 5 by Letters Patent, is:

1. In means of the character set forth, the combination of a bracket provided with a channel, a coiled wire member extending into said channel, and a pin entered in said 10 coiled wire member within said channel and causing cramped engagement between said channel and coiled wire member.

2. In means of the character set forth, the combination of a curtain-rod provided with 15 coiled wire end portions, brackets provided with channels receiving said end-portions, and members extending into the ends of said coiled wire portions and serving to cause cramped engagement between the same and 20 the walls of said channels.

3. The combination with a curtain-rod having a flexible coiled wire end-portion, of a bracket provided with a curved channel receiving said coiled wire end-portion, and a

pin entered in the end of said coiled wire 25 portion and causing cramped engagement between the same and the walls of said curved channel.

4. The combination with a frame, of a pair of brackets attached thereto and provided with channels, a curtain-rod having flexible coiled wire end-portions extending into said channels, and pins extending into 30 said channels from the opposite ends thereof and entered in the ends of said coiled wire 35 portions and causing cramped engagement with the walls of said channels.

5. The combination with a frame, of a pair of brackets secured thereto and equipped with curved sleeves, a curtain-rod having 40 flexible coiled wire end-portions extending into said curved sleeves, and substantially straight plugs entered in the extremities of said coiled wire portions and causing 45 cramped engagement between the same and the walls of said sleeves.

GUSTAF A. CARLSON.
